UNITED STATES PATENT OFFICE.

GEORGE WASHINGTON TRAMMELL AND WILLIAM McDUFFIE, OF ROME,
GEORGIA.

DRIER.

SPECIFICATION forming part of Letters Patent No. 690,796, dated January 7, 1902.

Application filed April 27, 1901. Serial No. 57,729. (No model.)

To all whom it may concern:

Be it known that we, GEORGE WASHINGTON TRAMMELL and WILLIAM McDUFFIE, citizens of the United States, residing at Rome, in the 5 county of Floyd and State of Georgia, have invented new and useful Improvements in Driers, of which the following is a specification.

This invention relates to improvements in 10 driers used for drying brick, lumber, or the like material.

The object of the invention is to provide means for equally distributing heat in the drying-chamber to the material placed therein.

15 A further object of the invention is to provide in a drying-kiln a series of flues which are connected to a single furnace, whereby the heat is materially assisted in being equally distributed.

20 A further object of the invention is to provide a drying-kiln wherein the products of combustion from the furnaces do not come into contact with the material being dried.

Many other objects and advantages will be 25 hereinafter referred to and be particularly pointed out in the claims.

In the drawings, Figure 1 is a side view of 30 the improved drying-kiln. Fig. 2 is a section on an enlarged scale, showing more clearly the details of construction of the flues. Fig. 3 is a top plan view with parts broken away to disclose the construction of the flues. Figs. 4, 5, and 6 are transverse sections on the lines 4 4, 5 5, and 6 6 of Fig. 3. Fig. 7 is a detail 35 view of a portion of the roof, showing the details of construction thereof.

The same characters refer to like parts in all the figures.

1 represents the outer casing of the drying- 40 chamber, 2 the furnaces, and 3 sheds or coverings at each end of the kiln.

The drying-chamber consists of the side 45 walls or casing 1, floor *a*, and roof *b*. The roof is made up of the usual rafters *c*, and on the under side thereof is a covering of corrugated sheet metal *d*, provided with a layer of sand *d'*, and on the tops of the rafters are secured tight-fitting boards *e*, and over this is placed some fireproof material.

50 The furnaces 2 are each composed of side

walls 4 4, arches 5, and grate 6, forming a combustion-chamber 7 and ash-pit 8. The combustion-chamber 7 communicates with preferably two flues 9, which spread out from each furnace toward the kiln, from which point they run parallel with each other. The flues 9 are preferably made below the surface, are lined with brick, and run entirely through the kiln, and all enter a chimney 10, which is common to the whole set. 55

In each of the flues 9 adjacent the furnace is a central partition 13, extending a suitable distance into the kiln, said partitions supporting a layer of brick 14, the remainder of the flue beyond the brick 14 being covered 60 with sheet metal, as at 15. The purpose of covering the flues with brick at a point adjacent the furnace is to prevent the action of the heat destroying a lighter material, it being remembered that at this point the heat is 65 the most intense. On the other hand, after the covering of brick is passed the intensity of the heat has somewhat diminished and the influences will not be such as to destroy the metal covering; rather will a radiating-surface be formed. It will therefore be seen 70 that while the heat is greatest at the furnaces it does not escape as rapidly as it will when the sheet-metal covering is reached. Hence 75 an even and uniform temperature can at all 80 times be maintained in the drying-chamber.

A second arch 5^a is built over the arch forming the top of the furnace, and between the two an air-space 16 is formed, communicating with the atmosphere through an opening 85 17, which is controlled by a damper 19. This air-space at the rear communicates with a flue 19^a, located over the combustion-flues, and opens into the kiln.

At the opposite end of the kiln and in the 90 roof thereof is the chimney 18 for carrying off the water-smoke and causing a complete circulation of air to the material being dried. The chimney is built of such height as to create a sufficient draft, at the same time not to 95 such an extent as would in any wise affect the maintaining of a predetermined temperature in the drying-chamber. To further assist in circulating the heated air through the kiln, a series of ventilators 19^x are arranged at a 100

point behind the chimney 18, said ventilators being of such height as to not materially affect or draw from the chimney.

Extending lengthwise of the kiln are a suitable number of tracks 20, and cars 21 are designed to run thereon, and at each end of the kiln are doors 22, which work up between the walls of the casing.

The operation of the improved drying-kiln is substantially as follows: The cars are brought up to the receiving end 23 of the drying-chamber, the door 22 being opened, and the car is pushed in on the tracks 20, and by reason of said tracks inclining a little the car 15 will roll down toward the delivery end 24. After a sufficient number of cars carrying the material to be dried have been placed in the drying-chamber the door 22 is closed and the fires kept going. The heat from the furnaces 20 passes through the lower flues to the chimney 10, and in so doing it is equally disseminated. At the same time the damper 19 is opened, and air from the atmosphere is admitted to the air-space 16, and by the time the air reaches 25 the drying-chamber it becomes thoroughly heated, and this heated air passes through and around the material being dried and absorbs the moisture, which is carried off through the chimney 18 and the ventilators 19.

30 Dampers 25 are provided in each flue to regulate the exit of the products of combustion and at the same time assist in maintaining a predetermined degree of temperature in the drying-chamber.

35 Having thus fully described our invention, what we claim as new, and desire to secure by Letters Patent, is—

1. An apparatus of the class described, comprising a drying-chamber, furnaces, combustion-flues leading from said furnaces and extending under the drying-chamber, air-heating chambers, flues arranged immediately above and in proximity to the combustion-flues and running parallel therewith, said 40 flues communicating with air-heating chambers and the drying-chamber, tracks situated above the flues, and means to support and carry the material being dried.

2. An apparatus of the class described,

comprising a drying-chamber, a plurality of 50 furnaces outside of and below said chamber, combustion-flues branching from said furnaces and running entirely under said drying-chamber, a chimney common to all of said flues, an air-heating chamber in each furnace, flues located above and in alinement with the combustion-flues, said flues communicating at one end with the air-heating chambers, and their opposite ends extending within and communicating with the drying-chamber, a chimney communicating with the drying-chamber, tracks located above both sets of flues, and means for supporting and carrying the material to be dried.

3. An apparatus of the class described, 65 comprising a drying-chamber, a furnace having an air-passage in its walls, combustion-flues communicating with said furnace and extending throughout the length of the drying-chamber, a partition in said combustion-flues extending from the furnace to a point within the drying-chamber, a layer of brick forming the top of the flues and supported by said partition, a layer of sheet metal covering the top of the remainder of the flues, and 70 a flue opening at its inner end into the drying-chamber and communicating at its opposite end with the air-space formed in the furnace, substantially as described.

4. An apparatus of the class described 80 comprising a drying-chamber, a roof covering said chamber, said roof consisting of a covering, a corrugated metallic ceiling, means for supporting said ceiling and a layer of sand covering the top of said corrugated ceiling, a 85 furnace, a series of flues under the drying-chamber which communicate with the furnace and the atmosphere, and means for circulating heated air through the drying-chamber, substantially as described.

90 In testimony whereof we have hereunto set our hands in the presence of two subscribing witnesses.

GEORGE WASHINGTON TRAMMELL.
WILLIAM McDUFFIE.
